UNITED STATES PATENT OFFICE.

ROY M. ALLEN, OF BLOOMFIELD, NEW JERSEY, ASSIGNOR TO WESTERN ELECTRIC COMPANY, INCORPORATED, OF NEW YORK, N. Y., A CORPORATION OF NEW YORK.

ELECTRICAL SWITCHING DEVICE.

1,415,972.

Specification of Letters Patent. Patented May 16, 1922.

Application filed August 13, 1920. Serial No. 403,210.

To all whom it may concern:

Be it known that I, ROY M. ALLEN, a citizen of the United States, residing at Bloomfield, in the county of Essex, State of New Jersey, have invented certain new and useful Improvements in Electrical Switching Devices, of which the following is a full, clear, concise, and exact description.

This invention relates in general to electrical switching devices and particularly to snap switches.

The invention provides a key for use in telephone or similar circuits where it is desirable to switch from one circuit to another with the smallest possible interval of elapsed time between the disconnection of the one circuit and connection with the other.

It is the object of this invention to provide a switch of the snap type which shall be simple, inexpensive to manufacture, and positive in operation.

These objects are accomplished by the invention in its preferred form by the use of a rotating slightly pointed lever operated cam, a roller member resiliently resting thereagainst and contact spring members against which the roller alternately snaps as the cam is rotated from side to side.

The invention may be better understood by reference to the drawings which illustrate the embodiment which the inventor prefers. Fig. 1 shows a general view of the invention; Fig. 2, shows the switch with portions of the frame cut away to show the details of the cam and its cooperation with the roller member; Fig. 3 shows a view of the switch in its position alternate to that of Fig. 1; Fig. 4 shows the details of the roller member.

On a suitable frame 1 is mounted a rotatable cam 2 pivoted on the shaft 3. The cam 2 is rotated manually by means of a lever 4. The frame 1 is preferably of the form described in E. B. Craft Patent No. 1,012,125 of December 19, 1911, although any suitable form may be used in the application of the general principles here involved. Contact spring members 5, 6, 7 and 8 are suitably mounted on the frame 1 preferably in the manner described in detail in the above mentioned Craft patent. Contact springs 5 and 8 rest against insulating blocks 9 and 10 fastened to the frame 1 by means of screws 11 and 12 respectively.

A shaft 13 carries a roller 14 of steel or

other wear resisting material, which rotates freely on the shaft 13. The roller 14 is provided with a bearing surface 15, and flanged edges 16 at either side of the bearing surface 15 to keep the roller centered on the cam 2. Rollers 17 also rotate on the shaft 13 and are positioned one on each side of the roller 14, being separated therefrom by the spacing washers 18. The shaft 13 and the shaft 3 are connected by coil springs 19 which hook over the ends of the two shafts, being held thereon in any suitable manner. Grooves 25 cut in the shafts satisfactorily hold them in place. The coil springs 19 are under tension pressing the roller 14 tightly against the edge of the cam 2.

The lower edge of cam 2 on which roller 14 travels, is pointed being provided with an apex 20. The edges of the cam recede from apex 20 so that the tension in the coil springs 19 pulls the rollers 17 over against either spring 6 or spring 7 depending upon which side of the roller 14 the apex 20 happens to be. The rollers 17 remain in such position while the cam is rotated to a point where the apex 20 bears upon the surface 15, as indicated in Fig. 2, when the roller 17 suddenly snaps to the other side. The time occupied in rolling from one set of springs to the other is very slight and is independent of the speed of operation of the cam 2.

Contact springs 6 and 7 are sufficiently resilient so that the pressure of the roller 17 against them is sufficient to cause them to contact with their corresponding contact springs 5 and 8 respectively.

The cam 2 is provided with shoulders 21 and 22 which cooperate with the frame 1 to limit the distance which the cam can rotate. In order to prevent rebounding of the cam 2 when the shoulders 21 and 22 strike the frame 1, shock absorbing springs 23 are fitted into apertures 24 cut in the cam 2.

What is claimed is:

1. In a switching device a plurality of switch members, a rotatable cam a roller member resiliently mounted to press against said cam whereby upon rotation of said cam, said roller member is caused to alternately contact the said switch members.

2. In a switching device, a plurality of switch members, a rotatable pointed cam, a roller member resiliently mounted to press

against said switch members and said cam and cooperate with said cam to operate said switch members alternately upon backward and forward motion of said cam.

5. 3. In a switching device, a plurality of switch members, a resiliently mounted roller means to operate said switch members, and a rotatable cam having two bearing surfaces cooperating with said roller means, said surfaces having increasing diameters and meeting at a common apex of greatest diameter.

10. 4. In a switching device, a plurality of switch members, a resiliently mounted roller means to operate said switch members, a rotatable cam having two bearing surfaces cooperating with said roller means, said surfaces having increasing diameters and meeting at a common apex of greatest diameter, shoulder means provided on said cam to

15. limit the rotation thereof, and shock absorbing means provided on said shoulder means.

20. 5. In a switching device, a supporting frame, a plurality of switch members sup-

ported by said frame, a roller means resiliently mounted on said frame to operate said switch members, a rotatable cam having two bearing surfaces to cooperate with said roller means, said surfaces having increasing diameters and meeting at a common apex of greatest diameter, shoulder means provided on said cam to cooperate with said frame to limit the rotation of said cam, shock absorbing means provided on said shoulder means, and lever means to rotate said cam.

25. 6. In a switching device, a plurality of switch members, a rotatable cam, and a member resiliently mounted on said cam and adapted reciprocate on the edge thereof whereby upon rotation of said cam said member is caused to alternately contact the

30. 35. switch members.

In witness whereof, I hereunto subscribe my name this 10th day of August A. D., 1920.

ROY M. ALLEN.
